UNITED STATES PATENT OFFICE

WILLIAM HANSON MINNIX, OF WASHINGTON, DISTRICT OF COLUMBIA.

DESIGN FOR A HANDKERCHIEF OR BANNER.

SPECIFICATION forming part of Design No. 18,530, dated August 14, 1888.

Application filed July 12, 1888. Serial No. 279,724. Term of patent 3½ years.

To all whom it may concern:

Be it known that I, WILLIAM HANSON MINNIX, a citizen of the United States, residing in the city of Washington, District of Columbia, have invented and produced a new and original Design for Handkerchiefs or Banners, of which the following is a specification, reference being had to the annexed drawing, forming part thereof, which represents my new design.

My design is especially intended for that class of handkerchiefs known as "bandana handkerchiefs;" but its use may be extended to other handkerchiefs or to banners.

The leading feature of my design consists in a picture representing a forest of hickory trees surmounted by an American flag and surrounded by hooks united and representing an endless band.

Referring to the annexed drawing by letters, A designates a field which is bordered by thirty-eight hooks linked together and forming a border, B. Within this field A, and prominently presented in the foreground, on the right-hand side thereof, is a representation of a hickory tree, C, and in the background a forest of similar trees in perspective is represented. On the left-hand side of the field A rises a flag pole bearing prominently at the caption of the field a United States flag, D, waving above the forest of trees and forward of the tree C. Near the four corners of the handkerchief or banner, outside the border B, separated links E E, in pairs, are represented. These may be omitted, if desired.

What I claim is—

The design for a handkerchief herein shown and described, the same comprising a field having upon it the representation of a portion of a forest with a United States flag above and forward of it, and the whole surrounded by a border composed of united hooks, as set forth.

WILLIAM HANSON MINNIX.
